(57) **CLAIM**

The ornamental design for an interdental cleaner, as shown and described.

DESCRIPTION

The patent or application file contains at least one drawing executed in color. Copies of this patent or patent application publication with color drawing(s) will be provided by the Office upon request and payment of the necessary fee.

1. Interdental cleaner

Figure 1.1 is a perspective view of an interdental cleaner;
Figure 1.2 is a front view thereof;
Figure 1.3 is a back view thereof;
Figure 1.4 is a top view thereof; and
Figure 1.5 is a bottom view thereof;
Figure 1.6 is a left view thereof;
Figure 1.7 is a right view thereof;
Figure 1.8 is an exploded view thereof; and
Figure 1.9 is a front view thereof.

Figure 1.9 shows hands holding the interdental cleaner. The hands are shown as environment only and to show the interdental cleaner in a state of use and form no part of the claimed design.
